UNITED STATES PATENT OFFICE.

HENRY M. CROWTHER, OF KINGMAN, ARIZONA.

AEROPLANE SAFETY-PARACHUTE AND MEANS OF LAUNCHING SAME FROM AERO- PLANES.

1,327,592.

Specification of Letters Patent.

Patented Jan. 6, 1920.

Application filed April 4, 1919. Serial No. 287,628.

To all whom it may concern:

Be it known that I, HENRY M. CROWTHER, a citizen of the United States, residing at Kingman, in the county of Mohave and 5 State of Arizona, have invented a new and useful Aeroplane Safety - Parachute and Means of Launching Same from Aeroplanes, of which the following is a specification.

10 My invention relates to improvements in man carrying parachutes in relation to method of launching the same from aeroplanes in flight and to the system of carrying and the method of launching the same 15 for life saving purposes from aeroplanes in flight; and the objects of my invention are to provide means of enabling a man carrying parachute to be instantly launched with the aviator (previously attached to suspension line system of the parachute) from an aeroplane or airship when the same is out 20 of control or falling to earth. The parachute being carried in a suitably covered case or container, with a snap hook attached 25 to the end of the parachute suspension ropes and by the use of the snap hook; the parachute to be attached to a body and shoulder harness worn by the aviator. The parachute is to be rapidly launched by the firing 30 of a shell or projectile from a gun, which is permanently loaded and carried in position for instant discharge; and the shell to have means of attaching a towing line at the time of loading the gun; and this tow 35 line to be attached at opposite end to the top of the parachute; ready to be launched, with the object that when gun is fired, the shell or projectile will be forcibly shot upwardly into the air above the falling aeroplane, carrying the tow line with it and 40 when the tow line is fully drawn out, the attached parachute is launched from its case; the parachute being drawn upwardly by its top end in collapsed, fully strung out 45 position, and when completely drawn out of its case, the parachute will be stopped in vertically suspended position in the air above the aeroplane by the weight of the aviator previously attached as explained; 50 and the shell or projectile continuing to rise exerts a strain on the tow line sufficient to cut its tow line free from the parachute by automatically bringing a cutting knife into play at this time, leaving the shell or projectile and its attached tow line free to fall

to earth, leaving the parachute momentarily suspended vertically in fully strung out collapsed condition in the air above the aeroplane, while the aviator to whom the parachute is attached and the aeroplane continuing to fall will result in the parachute opening in the usual manner and arrest the speed of the falling aviator and pull him free from the aeroplane, to descend to earth slowly by use of air resistance of distended parachute. All of this action taking place automatically in a few seconds after aviator fires the shell or projectile, with the tow line attached, from the loaded gun.

I attain these objects by the apparatus 70 illustrated in the accompanying drawings, in which,

Figure 1 is a vertical section of an aeroplane in horizontal flight, showing the position of carrying the gun, and the parachute, 75 and the other apparatus.

Fig. 2 is a vertical section of the top of the parachute, showing attachment gear, and the cutting loose device, of the tow line and shell launching system.

Fig. 3 is a vertical section of the cutting knife that automatically releases the shell or projectile with tow line attached, from the parachute.

Fig. 4 is a vertical section and view of 85 the case or container for the tow line. The case or container for carrying parachute is the same in detail but is proportionately larger in size.

Fig. 5 is a vertical section of the gun in 90 which the cartridge is inserted, containing the shell or projectile to which the tow line is previously attached, all ready for instant discharge.

Fig. 6 is a vertical section of shell or projectile and its case or cartridge, showing method of loading, and also showing a section of the tow line attached.

Similar numerals refer to similar parts throughout the several views.

Fig. 1 shows the aeroplane 1, and gun 2, loaded with cartridge and a shell with a tow line attached to the shell; and tow line container 9^a, with tow line 7 coiled therein, with one end of tow line attached to the shell 3 in place in cartridge 3^a, in place in breech of the gun; the tow line being coiled ready to feed out the line from top of coil downwardly, and when bottom of the coil of tow line is reached the line continues to 110

- the other end of tow line where it is attached to parachute 11, from the top of parachute; the parachute is contained in case or container 9, with the fabric upper part resting on top of the suspension rope gear of parachute; and attached to the lower end of the parachute suspension rope system is a rope line 12 passing out of case 9 along the front inner side of same, which 5 part resting on top of the suspension rope gear of parachute; and attached to the lower end of the parachute suspension rope system is a rope line 12 passing out of case 9 along the front inner side of same, which 10 rope line 12 terminates in an attached snap hook 12^a, for purpose of attaching parachute suspension line system to a conventional harness gear (not shown) to be worn on shoulders and upper body of aviator. 15 The tow line container and parachute container are each covered with a separate cloth cover 9^b, and 9^c, shown in detail in Fig. 4, with object of retaining the contents of the containers from spilling out when aeroplane 20 is in the upside down position; and these covers consist of a circular hoop 29 formed to fit loosely over the top end of each case or container, respectively, and over the top of the hoop is stretched a canvas cover which 25 is riveted to the sides of hoop, to form a slip on cover or lid for each case; the hoop having two small grooves 31 and 32 located opposite sides and formed in the side walls of the hoop, and these grooves extend outwardly from main circle of hoop circumference, and in direction of longitudinal axis of side of hoop, with object to provide a 30 groove to permit tow line 7 to enter container interior between wall of container 35 (outside) and hoop of cover, thus permitting ends of tow line to enter and continue out of the case with cover in place on case. The hoop exterior has attached to its outside wall and extending downwardly, a lug 32 40 terminating in a projection that engages a hook 34 attached to side of container or case, near its top, to form one side of a latch for covers to cases 9^b and 9^c, respectively of each case; and on opposite side of hoop side exterior wall is similarly attached a swinging latch 56, consisting of a hinge 57, a flat tension spring 58, to hold swinging latch in place against jarring out of locked position, and a lower swinging portion 59^a having a crescent shaped arm 59, with a projection to engage a stop piece 60 secured to the side of the case or container, with the object to provide a lock latch for the cover of the container or case, in each container; 55 and the cover opens automatically as follows: The tow line on its course as strung in position in each container leading from projectile to parachute is passed under the crescent shaped arm of the cover latch of 60 both container covers and is secured to said arm lightly by tying with a piece of thread, to avoid its swinging out of position, and when the projectile is discharged from the gun the tow line in paying out will raise 65 the cover after releasing the latch, first of

the tow line container and later the cover of the parachute container, and the covers will fall overboard.

The covers are purposely made light in weight in case of their striking the aviator, 70 when released.

With the covers off the tow line and parachute are free to be launched without interference.

Fig. 5 shows the gun, with smooth bore 75 barrel 2, with open breech, the gun is attached to the fuselage of the aeroplane by hanger arms 35 and 35^a; and said gun has a conventional breech block 36, with lock groove engaging projection lugs 36^a, in the 80 usual manner, and the cartridge end of gun barrel has an offset groove 38 to engage the projecting rim of cartridge end. The breech block has a firing pin 37 with stop pin 37^a, engaging a slot groove in firing pin, to hold 85 pin in place, and a cylindrical striking hammer bolt 39 slidably mounted in a cylindrical hole through the center of the breech block longitudinal axis, which hammer bolt is surrounded by a compression coil spring 90 41 having a seat 39^b formed integral with the hammer bolt. The spring is held in place in the breech block by a spring seat screw cap 42 mounted on the threaded rear end of the breech block, which cap 42 has a 95 centrally located hole to pass the rear end of the hammer bolt through it.

The hammer bolt extends a short distance beyond the end of the breech block, and terminates in a hand hold ring 40, with the 100 object to provide means of cocking the hammer by drawing the hammer bolt backward. The hammer bolt has a projecting circular lug 39^a located about midway of its length, formed integral, with a face at right angle to its length, at the front end of the lug, to engage the firing trigger pin 44 when the hammer bolt is cocked, and the lug has a tapered rear end to raise the firing trigger pin over the lug 39^a when the hammer bolt 115 is drawn backward. The firing trigger pin 44 is slidably mounted in a hole bored in the side of breech block, and has a compression coil spring 45 mounted on it, which spring is seated on a lug made integral with a firing trigger pin and is retained with a screw cap 43, having a central hole to pass the end of the pin through, and the pin terminates in an eye hole to attach a firing control wire 46 which terminates in a handle 120 hold 47, held in a safety clip (not shown) convenient to the hand of the aviator. The control wire 46 may pass over a roller 48.

No special novelty or invention is claimed for the detail of the gun shown in Fig. 5; 125 a spring powered or compressed air gun would serve the purpose but might weigh more than the explosive cartridge gun as illustrated. Fig. 6 shows the loaded, cylindrical cartridge case 3^a, and projecting rim 130

48, charge of explosive 50, retaining wad 51, the shell or projectile 3 and reamed inwardly mouth of cartridge case 57, the object of which is to retain the shell. The shell 3 has 5 a conical shaped forward end 52, and an interior space 53 opening into the rear end of the shell body and a screw end bolt 54 centrally located in the interior space end or back, which bolt 54 terminates in an eye 10 hole 55 to provide anchorage for the end of the tow line 56, which is a section of chain attached to main tow line 7. The cartridge 3^a is provided with a center fire percussion exploding cap 49.

15 Upon discharge of the shell from the gun, the shell is intended to reverse itself and travel point forward.

The gun is kept loaded and trigger cocked during flight of the aeroplane and tow line 20 attached to shell and parachute top end and the parachute is ready in container for instant use.

Upon getting into the aeroplane the aviator snaps the hook on end of the 25 parachute suspension line to his shoulder and body harness which he will wear. The ordinary features of the parachute are of conventional type, usually of about 35 feet in 30 opened diameter, with 55 feet of suspension line system and provided with 12 inch air outlet in top, but Fig. 2 shows details of special features of my invention in their relation to common features of conventional 35 parachute, of which 11 is fabric of parachute body, with air discharge hole 11^a. Heavy reinforcement strips of fabric 18 are shown in which a fiber rope 19 is anchored, and this rope 19 extends across the air hole opening and is fastened at both ends to 40 parachute at points of the reinforcement; and mounted stationary on the rope 19 are two wooden stop blocks of circular disk shape, 20 and 20^a, to serve as stops to hold the tow line, etc., in place; and there is 45 mounted slidably on the rope 19 between the stop blocks, a bolt 17 with an eye hole 21 in the end, through which the rope 19 is passed, to provide a tie for the tow line to the parachute; and bolt 17 has a corrugated 50 section at other end, against which corrugations the ends of a plurality of rubber ribbons 14 are anchored by string winding 16, the rubber ribbons are of sufficient length to serve as shock absorbers for the tow line, 55 and the other end of the rubber ribbons are attached to the end of the tow line 7 at string winding 15; and the tow line other end is attached to the shell or projectile in the gun, as described, this tow line is of 60 a suitable length, about 200 feet, and may be fire-proofed for the portion that is exposed to the flash of the explosion of the gun, in addition to the short length of chain directly connected to the shell or projectile. 65 Mounted on the parachute anchor fiber rope

19 between stop blocks 20 and 20^a is a cutting device 22, to which is attached a jerk line 24 at the eyelet hole fastening 23; and this jerk line 24 extends downwardly in the interior of the parachute and its lower end 70 is attached to the lower end of the parachute suspension ropes terminal, but the jerk line is, in length, several feet shorter than the total distance from top of the parachute to the end of the suspension ropes terminals 75 when the parachute is fully collapsed and stretched out in its longest over-all condition, with the object that when parachute is fully towed out of its case by the movement of the discharged shell or projectile and the 80 tow line connection to a distance from the aeroplane which will produce a strain on the weight of the attached aviator, the jerk line being shorter will not be allowed to move as far as the parachute, thus bringing 85 the jerk line to an abrupt stop while the parachute still continues to be pulled upward by the tow line and shell or projectile with result that the cutting device 22 is 90 forcibly pulled down on the anchor fiber rope 19 by the strain on the jerk line to which cutting device is attached, and the knife edges of the cutting device sever the anchor fiber rope and permit the tow line and the shell or projectile attached thereto 95 to be released from connection with the parachute leaving the parachute fully launched in the air, ready to open and lift the aviator from the aeroplane.

Fig. 3 shows detail of the cutting device, 100 of which 22 is a frame of open interior, triangular in shape, mounted with large end down, and mounted on both sides of interior along the length of the frame are double knife blades 25, with cutting edges facing inwardly parallel to length of frame, with cutting edges spaced a fixed distance apart at lower end and meeting at a point in upper part of frame; the cutting edges do not reach entirely to bottom of frame, thus providing space free of knives for passage of the fiber rope 19. The lower end of frame forms a plain bend 23 in which is located an eye hole 22^a, in which hole is anchored the end of the jerk line 24; and there is provided a flat spring 26 bent to form a guard to hold the anchor rope 19, which is passed through the lower part of frame and rests on the plain bent portion 23, away from contact with the knives, ordinarily, or until the cutting device is forcibly pulled down by jerk line tension as explained; and the spring clip or guard 26, has an anchorage 27 and spring tension stop 28, the tension of the spring guard being designed to 110 permit the fiber rope 19 to be released to contact with the knives, in manner described.

The size of bore and length of gun barrel, the weight and size of the shell or projectile 130

and measured amount of a slow igniting powder used are all to be nicely proportioned with respect to object in view.

Various changes may be made in detail of 5 this apparatus without departing from the spirit of my invention as claimed.

I claim:

1. The combination of an aeroplane with a safety parachute, comprising a parachute 10 adapted to be carried on the aeroplane, means attached to a parachute for projecting it away from the aeroplane, and means whereby the projecting means becomes inoperative and detached from the parachute when the 15 parachute is fully drawn out.

2. The combination of an aeroplane with a safety parachute, comprising a parachute adapted to be carried on the aeroplane, means for projecting the parachute away 20 from the aeroplane connected with a loose tie to a rope across a hole in the top of the parachute, a jerk line having one end fixed to the aeroplane and carrying a cutting knife mounted on a rope at the other end, 25 the jerk line being of such length that when the parachute has been fully drawn out by the projecting means the jerk line will be drawn taut and the rope across the hole in the top of the parachute will be cut by the 30 knife, thereby freeing the parachute from the projecting means, and means for connecting the parachute with the harness of the aviator.

3. The combination of an aeroplane with 35 a safety parachute, comprising a parachute adapted to be carried on the aeroplane in a properly constructed case opening upwardly, projecting means for projecting the parachute away from the aeroplane, a tow

line connecting the projecting means with 40 the parachute by a loose tie on a rope across a hole in the top of the parachute, a casing opening upwardly for the tow line, a cover for the tow line casing adapted to be jerked off the casing when the tow line is being 45 operated by the projecting means, a cover for the parachute casing adapted to be jerked off by the tow line rope when the line is operated by the projecting means, and means for connecting the parachute with the harness of the aviator. 50

4. The combination of an aeroplane with a safety parachute, comprising a parachute adapted to be carried on the aeroplane, a gun mounted upon the aeroplane pointing 55 upwardly and adapted to be fired by means positioned in easy reach of the aviator, a projectile for the gun, a tow line connected with the projectile at one end and with the parachute at the other end, means for releasing the tow line from the parachute when the parachute has been fully drawn out by the flight of the projectile, and means for connecting the parachute with the harness of the aviator. 60

5. The combination of an aeroplane with a safety parachute, means for projecting the parachute, a container for the parachute opening upwardly, a cover for the container having a latch adapted to be operated by a 65 tow line connected with the parachute, a second container adapted to carry a tow line and having a cover carrying a latch adapted to be operated by the tow line when the said tow line is operated by the projecting 70 means. 75

HENRY M. CROWTHER.
